Primary Examiner — Katherine Glennon*Assistant Examiner* — Yuan Yuan(74) *Attorney, Agent, or Firm* — Minder Law Group,
Willy H. Wong(57) **CLAIM**

The ornamental design for a shark bubble toy, as shown and described.

DESCRIPTION

FIG. 1 is a front view of a shark bubble toy in accordance with the present invention.

FIG. 2 is a rear view thereof.

FIG. 3 is a top view thereof.

FIG. 4 is a bottom view thereof.

FIG. 5 is a left side view thereof; and,

FIG. 6 is a right side view thereof.

The broken lines show portions of the shark bubble toy that form no part of the claimed design.
